UNITED STATES PATENT OFFICE

164,594

CLOCKCASE

Carl Otto, New York, N. Y., assignor to General
Electric Company, a corporation of New York

Application June 29, 1951, Serial No. 15,707

Term of patent 14 years

(Cl. D42—7)

To all whom it may concern:

Be it known that I, Carl Otto, a citizen of the United States, residing in New York, in the county of New York, State of New York, have invented a new, original, and ornamental Design for a Clockcase, of which the following is a specification, reference being had to the accompanying drawing, forming a part thereof.

In the drawing,

Fig. 1 is a front view of the clockcase showing my new design;

Fig. 2 is a side elevational view of the clockcase, mostly in diagrammatic outline; and

Fig. 3 is a fragmentary rear elevational view of the lower portion of the clockcase.

I claim:

The ornamental design for a clockcase, as shown.

CARL OTTO.
